UNITED STATES PATENT OFFICE.

GRAHAM I. FRANCIS, OF COVENTRY, ENGLAND.

DESIGN FOR A CYCLE PEDAL-FRAME.

42,170.

Specification for Design.

Patented Feb. 13, 1912.

Application filed January 9, 1909. Serial No. 471,536. Term of patent 14 years.

To all whom it may concern:

Be it known that I, GRAHAM INGLESBY FRANCIS, a subject of the King of Great Britain, residing at Coventry, in the county of Warwick, England, have invented a new, original, and ornamental Design for Cycle Pedal-Frames, of which the following is a specification, reference being had to the accompanying drawing, forming part thereof.

Figure 1 of the drawing is a plan view of a cycle pedal frame, showing my new design, and Fig. 2 is an edge view thereof.

I claim:

The ornamental design for a cycle pedal frame, as shown.

GRAHAM I. FRANCIS.
